UNITED STATES PATENT OFFICE.

LEVI W. FIFIELD, OF WORCESTER, MASSACHUSETTS, ASSIGNOR TO THE
KNOWLES LOOM WORKS, OF SAME PLACE.

SHUTTLE FOR TAPE-LOOMS.

SPECIFICATION forming part of Letters Patent No. 351,259, dated October 19, 1884.

Application filed August 21, 1884. Serial No. 141,110. (No model.)

To all whom it may concern:

Be it known that I, LEVI W. FIFIELD, a citizen of the United States, residing at Worcester, in the county of Worcester and State 5 of Massachusetts, have invented certain new and useful Improvements in Shuttles for Tape-Looms; and I declare the following to be a description of my said invention, sufficiently full, clear, and exact to enable others skilled 10 in the art to which it appertains to make and use the same, reference being had to the accompanying drawings, which form a part of this specification.

The objects of my present invention are to 15 make a shuttle for use in the looms specified, the construction of which will be more convenient, durable, and efficient than that of those heretofore in use, and to construct the body of the shuttle in such manner that the 20 parts subject to wear can be renewed.

To attain these objects my invention consists 25 in a shuttle, the construction, arrangement, and operation of which are shown in the drawings and explained in the following description, the particular subject-matter claimed 30 being hereinafter definitely specified.

In the drawings, Figure 1 is a plan view of 35 my improved shuttle, a portion at one side being shown broken away to reveal parts beneath, also a part of a shuttle-guide. Fig. 2 is a section at line *w w* of Fig. 1, the bobbin being removed. Fig. 3 is a section at line *x x* of Fig. 1, showing the shuttle and its guide and an operative gear. Fig. 4 is a section at line *y y* 40 of Fig. 1. Fig. 5 shows an end, side, and section of the eye-bushing. Fig. 6 is a view of one of the rear ends of the front or bow of the shuttle-frame, showing the groove and lip for hinging and retaining the frictional presser-arm. Fig. 7 is a similar view of the other 45 rear end of the bow, showing the groove or seat for confining the presser-arm spring; and Fig. 8 is a sectional view, showing the manner of retaining the spindle-holding spring.

In referring to parts, A denotes the wood or body of the shuttle. As a feature of improvement in this I form the back or straight portion, *a*, in a separate piece from the bow or forward portion, *a'*, the parts being fitted 50 to each other, as shown, with a longitudinal

ledge or offset along their line of junction, *a'*, and rigidly secured together by screws *a*³, or equivalent fastenings. This construction permits of the back *a* being removed when the guiding-grooves *b* or racks *c* become worn to 55 a degree that interferes with proper action, and of a new back being attached to the bow *a'*, thus avoiding the necessity of renewing the entire shuttle when the part subjected to the greatest wear is the only portion requiring 60 repair.

B indicates the guide block or plate, on which the shuttle is supported and guided when in use, and C one of the gear-wheels, by which the shuttle is propelled through the 65 shed of the warp in the usual manner. Said guide and gear are hereinafter more fully described.

D indicates the spindle, E the bobbin, and F the friction pad or brake.

The arm *f* or wire that supports the pad F has its end bent at a right angle (see dotted lines, Fig. 2) and laid into a groove, *e'*, formed in the end of the bow *a'*, where it is retained by the back *a*, so as to form the hinge or center on which the arm swings. A lip of the wood, as at *c*, Figs. 2 and 6, extends across the exterior and prevents the wire from being drawn out of the groove *e'*. The spring *F'*, that presses against the arm *f*, has its rear end 70 confined in a longitudinal groove, *f'*, between the parts *a* and *a'* of the body, and is so arranged that by loosening the screws *a*³ and moving said spring longitudinally in its seat *f'* it can be adjusted to bear on the arm at a 75 position nearer to or farther from its hinge end, and thus give a greater or less frictional force of the pad F upon the bobbin E.

A spring, E', having a suitable depression or hole for receiving the point of the spindle 80 D, is arranged within a suitable recess, *g*, formed in the wood of the bow *a'*, (see Fig. 1,) which spring serves to press the spindle toward the opposite side of the bow and retain its head in the groove *d*. Said spring is 85 retained in place by means of its backward-turned end *E'*, which is embedded into the frame or placed between the bow *a'* and back *a* of the body-wood, and there clamped when the screws *a*³ are tightened.

The spindle D is of substantially ordinary form. Its end is pointed to fit the depression in the spring E', and it is inserted in the shuttle by forcing its point against the spring and slipping its head, which is offset and beveled, as shown, into the groove d. The groove being undercut retains the spindle in place.

Across the forward part of the bow a', I arrange a wire or rod, H, and upon this rod is placed a small coiled-wire spring, I, confined between two beads or slides, i i, that run loosely upon the rod, and small rings J J' are arranged on the rod outside the beads. The spring I acts by expansion to force the rings J J' apart or to the ends of the rod H.

In the threading of the shuttle the thread t from the bobbin is wove through a ring, r, which is loosely attached to the front of the bow a', then through the ring J and the opposite ring, J', and from thence out through the eye-bushing K at the front of the shuttle. Strain on the thread tends to draw the rings J J' and sliding beads i i together and compress the spring I, and slack of the thread is taken up by the expansion of the spring I. This take-up device works very freely and sensitively, is simple and convenient, can be easily constructed, and is not liable to get out of order.

The eye-bushing K is made, as shown in Fig. 5, with a screw-thread cut on its exterior, and it is screwed into the opening formed in the front of the body, as indicated. By threading the bushing I avoid the usual liability of the bushing working loose and coming out of the shuttle, and also render it possible to change its position or partially turn it around, when the thread has worn grooves in its sides, so as to bring a new part of the surface to the wear. The plate or guide-block B, on which the shuttle is mounted for action, consists of a single piece of sheet or thin metal having an offset head or overhanging flange, b', which works in a corresponding - shaped kerf or groove, b, formed in the wood body of the shuttle. This guide-plate is secured to the lathe or bat-

ten of the loom at such position that the shuttle will properly pass through the warp-shed in traveling from one guide-block to another, the movement of the shuttle being effected by 50 gears C and their actuating racks in ordinary manner.

What I claim as of my invention, and desire to secure by Letters Patent, is—

1. The combination, with the body A, composed of the parts a a', arm f, and frictional presser F, of the spring F', having its end confined between the parts a and a' in a longitudinal groove, f', and adapted for longitudinal adjustment, substantially as and for the 60 purpose set forth.

2. The combination, with the shuttle-body formed in two parts, one of which is provided with the lateral groove e' and the overhanging lip e, of the friction presser-arm f, having 65 its end bent at an angle and laid into said groove and confined by said lip, as set forth.

3. The combination of the bobbin-supporting spindle D, having an offset beveled head, with the shuttle-body provided with the bow 70 having the undercut beveled groove d at one side for receiving said spindle-head and a recess, g, at the opposite side, and a spring located within said recess and furnished with a hollow or depression to receive and hold the 75 point of said spindle, and a backward-turned end set into the frame, whereby said spring is retained in position, substantially as set forth.

4. The combination, with the shuttle-frame provided with the bow a', having the eye K, 80 and the bobbin-supporting device, of the rod H, the guide-rings J J', slides i i, and spring I, mounted on said rod, and the guide-ring r, connected with the shuttle-frame, substantially as and for the purposes set forth.

Witness my hand this 19th day of August, 85
A. D. 1884.

LEVI W. FIFIELD.
